Herman E. Wusche, of Philadelphia, Pa.

Assignor to

Robert Wood, of Philadelphia, aforesaid.

Letters Patent No 762. Dated Feb. 12, 1856.

The schedule referred to in these Letters Patent, and making part of the same

To all whom it may concern,

Be it known that I, Herman E. Wusche, of the City of Philadelphia, in the County of Philadelphia, & State of Pennsylvania, have invented or produced a new & original design for a gate, & I do hereby declare that the annexed drawing is a correct & faithful representation of the design at a small scale, to be used to form a pattern for gates for cemetery & other railings. The design is in the gothic style, an oge arch flanked by buttresses richly crocketed & topped with finials; between the buttresses it is filled with gothic ornamental tracery.

I claim the design as represented & described in this specification, & in the drawing.
